UNITED STATES PATENT OFFICE.

GEORGE HENRY PRESTON, OF LONDON, ENGLAND.

COOKING AND HEATING STOVE.

Application filed June 18, 1923. Serial No. 646,177.

To all whom it may concern:

Be it known that I, GEORGE HENRY PRESTON, a subject of the King of Great Britain, residing at 3 Willow Avenue, Barnes, London, S. W. 13, England, have invented new and useful Improvements in and Relating to Cooking and Heating Stoves, of which the following is a specification.

This invention relates to improvements in stoves for the purpose of heating, baking, boiling, and hot water supply.

Hitherto with stoves of this description where an open fire grate is combined with an oven and boiler, it has been found necessary to use two or three separate dampers for regulating the flues leading from the fire direct to the chimney, to the boiler, and to the oven.

In a combined stove of the before mentioned type, and according to my invention, the canopy or like flue adjuster of the open fire grate besides regulating the flue direct to the chimney is connected to and adapted to operate a damper for regulating both the oven and boiler flues.

In one example, the flues leading from the boiler and the oven are brought together or led to a divided damper box, or casing, so as to be controlled by a single damper adapted to cover one or other of the said flues, the said damper being connected to the canopy of the open stove so as to be operated thereby in such manner that when the canopy is closed to its minimum opening the boiler flue is open and when the canopy is fully open or approximately so the oven flue is open and the boiler flue is closed.

Apart from the opening and closing of the boiler flue by the damper, the boiler is preferably so arranged as to be always exposed to the fire in the open grate so that the boiler is heated to a certain extent at all times.

The accompanying drawings show one construction of combined stove made in accordance with this invention.

Fig. 1 is a front elevation.

Fig. 2 is a plan, and

Fig. 3 a section on line X X of Figs. 1 and 2.

In the drawings, *a* is an open fire grate of the slow combustion type, *b* is a boiler of any usual or suitable type fitted at the back of the grate so as to be exposed to

the fire therein, *c* is the oven fitted against the side of the open grate, *b*¹ is the boiler flue which is led upwards at the back to the front chamber *d*¹ of a damper box *d*, the other and rear chamber *d*² of which is connected by a flue extension pipe *c*² to the oven flue *c*¹, which passes around the oven in the usual way.

At the side of the open grate *a* an opening *c*³ is provided communicating with a flue *c*⁴ which opens into the oven flue *c*¹ beneath the oven.

The damper box *d* is fitted with a sliding damper *d*³ adapted to cover one or other of the chambers *d*¹ or *d*² and thereby open or close communication between the oven or boiler flues and the chimney *e* beyond.

This damper *d*³ is connected by a rod and bracket, or other suitable connection *h* to the adjustable canopy *a*¹ of the open grate; the said canopy is of any usual or suitable construction according to the type of grate selected, for example, in some types of canopy the dampers may be connected to a cross bar fitted between the wings of the canopy instead of being connected by a rod and bracket *h* as shown, to the shutter plate *a*² of the said canopy.

The said shutter plate *a*² and the fire brick back *a*³ of the open stove are so arranged that a minimum amount of opening is left at *a*⁴ when the canopy and shutter plate are pushed inwards to their full extent.

It will be seen that in use the canopy *a*¹ of the open grate is utilized for opening or closing the oven flue or the boiler flue by means of the damper *d*³, thus allowing the three flues to be controlled by the movement of the one part, the open fire flue being never entirely closed owing to the provision of the minimum opening *a*⁴.

By closing the canopy *a*¹ the inward movement thereof through the connection *h* slides the damper *d*³ backwards until it covers the rear chamber *d*² of the damper box *d* and thus shuts off the oven flue, and the heat instead of passing to the oven passes through the boiler flue *b*¹ and chamber *d*¹ to the chimney *e* the minimum opening *a*⁴ still remaining above the open grate.

By opening the canopy the damper *d*³ is drawn forward so as to cover the chamber *d*¹ and thus open the oven flue to the chimney

e and close the boiler flue *b*¹; the heat now passes by the aperture *c*³, flue *c*⁴ under the oven to the center thereof and then around the oven body by flue *c*¹ and extension *c*² to the chamber *d*² and thus to the chimney *e*.

The opening and closing of the canopy *a*¹ thus effectively regulates the open fire and the boiler and oven flues as required.

Amongst other advantages of the construction shown it may be mentioned that the same damper box with damper is suitable for a large or small oven and the iron cheek will suit large or small ovens, the brickwork flue beneath the oven being altered accordingly. The flow and return pipes of the boiler may be connected to existing circulating pipes at the right or left hand of the chimney breast.

No bolts or screws need be provided to fix the oven to the stove as the oven rests on the base part which is provided with the central flue *c*⁴ and the connection to the flue extension *c*² is by a socket such as *c*⁵.

The boiler may be of any ordinary stock pattern, and the open stove may be of the slow combustion type with fire brick sections at back and sides whereby fuel is economized and the heat is radiated into the room.

What I claim as my invention and desire to secure by Letters Patent is:—

1. A stove consisting of the combination of an open fire grate provided with an adjustable canopy or the like, an oven, and a boiler, flues for said oven and boiler opening together in the chimney, a damper slidable to close either said oven or said boiler flue and connected to the canopy so as to be operated by the opening and closing movement thereof, substantially as set forth. 30

2. A stove consisting of the combination of an open fire grate provided with an adjustable canopy having a bracket fitted thereto, an oven, and a boiler, flues for said oven and boiler opening together in the chimney, a movable plate having a rod connection to the bracket of the canopy and capable of closing or opening the oven and boiler flues by raising or lowering said canopy, substantially as set forth. 40

3. A stove as in claim 2, provided with a divided damper box and damper covering the exits of the boiler and oven flues into the chimney, substantially as set forth. 50

Dated the 1st day of June, 1923.

GEORGE HENRY PRESTON.
